Des. 185,148
Patented May 12, 1959

185,148

VENDING MACHINE FOR DISPENSING HOT FOOD OR THE LIKE

Fred Hebel, Wilmette, Ill., assignor to Fred Hebel Corporation, Addison, Ill., a corporation of Illinois

Application November 22, 1957, Serial No. 48,608

Term of patent 14 years

(Cl. D52—3)

Figure 1 is a front view, slightly in perspective, of the vending machine for dispensing hot food or the like, showing by new design; and

I claim:

The ornamental design for a vending machine for dispensing hot food or the like, as shown.
